UNITED STATES PATENT OFFICE.

ALFRED R. MORRILL, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

WAX-THREAD-SEWING MACHINE.

Application filed December 5, 1917. Serial No. 205,610.

The invention relates to wax thread sewing machines, and more particularly to lock stitch shoe sewing machines of the class usually employed in stitching the outsole to the 5 welt of a welted shoe.

In operating machines of this class, the operator in removing the shoe after the machine has been stopped, draws off a sufficient length of thread to start the next seam, and 10 cuts the threads close to the shoe. This requires the time and attention of the operator, thus reducing the production of the machine, and it also involves a material waste of thread at the beginning of each 15 seam. It is the object of the present invention to eliminate this loss of time and waste of thread, thus increasing the capacity of the machine and decreasing the cost of production. To this end the invention contemplates the provision of means for severing the threads at the completion of the sewing, and for holding them until after the completion of the initial stitches at the beginning of the succeeding shoe. This ensures 20 the proper and uniform severing of the threads at the completion of each shoe, and enables the seam to be properly started on the succeeding shoe without waste of thread. The thread severing and holding means are 25 preferably actuated automatically upon stopping the machine, thus avoiding additional manipulation or attention on the part of the operator with its resulting loss of time. In embodying the invention in an outsole stitcher provided with mechanism for stopping the machine at the completion of the sewing with its parts in a predetermined position, it is preferred to control the thread 30 cutting and holding means from the stop mechanism, thus ensuring the proper timing of these devices.

In addition to the features outlined above, the invention includes certain further features of construction and combinations of 35 parts which are hereinafter described and set forth in the claims. The various features of the invention will be readily understood from an inspection of the accompanying drawings and the following detailed description of the mechanism illustrated therein.

In the drawings, Figure 1 is a front elevation showing so much of an outsole stitcher

as is necessary to illustrate the application of the present invention thereto; Fig. 2 is a plan view of the machine; Fig. 3 is a partial front elevation showing the thread cutting and holding devices and a part of their actuating mechanism; Figs. 4, 5, 6 and 7 are views showing details of said actuating mechanism; Fig. 8 is a detail side elevation showing the thread cutters and holders and their actuating mechanism; Fig. 9 is a detail plan view of the devices for cutting and holding the needle thread; Fig. 10 is a similar sectional plan view; Fig. 11 is a sectional view through the thread cutter and holder for the locking thread; Fig. 12 is a sectional view on line 12, Fig. 11; Figs. 13 to 26 are detail views showing the mode of operation of the thread cutters and holders; 50 and Fig. 27 is a sectional elevation showing the manner in which the operation of the thread cutters and holders is controlled from the stop mechanism.

In the drawings the invention is shown as embodied in a lock stitch shoe sewing machine having substantially the construction and mode of operation of the machine shown and described in Patents No. 1,169,909, February 1, 1916, and No. 1,233,539, July 17, 1917. This machine is provided with a curved hook needle 2, a looper 4, a thread arm 6, a loop taker in the form of a hook or shuttle mounted in the casing 8, a loop spreader 10, a curved awl 12, a work support 85 or table 14, a presser foot 16, a takeup 18, an auxiliary takeup 20, and the usual co-operating devices, all of which are actuated and operated substantially as in the machine of 90 said patents.

In embodying the preferred form of the present invention in this machine, two thread cutters and holders are combined with the stitch forming devices to sever the needle and locking thread at the completion of the sewing, and to hold the ends of the thread at the beginning of the next seam until the first stitch has been formed and the threads anchored in the work. As shown, the devices for cutting and holding each thread 100 are similar in construction and mode of operation. The cutter and holder for the needle thread comprises a rod 22 provided at its forward end with spring gripper fingers 24,

and carried in a surrounding sleeve 26 which is mounted to reciprocate in a guideway 28 in the work support. The rod is provided at its rear end with a radial projection 30 which passes through a slot in the sleeve and engages a slot 32 in the guideway. The ends of the slot 32 form stops for limiting the movement of the gripper rod with the sleeve in either direction, the continued movement 10 of the sleeve after the gripper rod has been arrested serving to close or open the gripper fingers. The end of the sleeve is provided with a cutter blade 34 for severing the thread after it has been seized by the gripper fingers. The blade 34 is located at the upper side of the tube and thus the thread is cut close to the shoe substantially in the plane of the work engaging surface of the work support. As a result of this arrangement 20 of the cutter together with the fact that the guideway for the sleeve 28 extends upwardly through the work support at an inclination to its upper surface a short or substantially no thread end is left projecting 25 from the work. The cutter and holder for the locking thread comprises a similar rod 36 provided with the spring fingers 38, and carried in a sleeve 40 which slides in a guideway formed in the bracket 42, the upper end 30 of the rod being provided with the radial projection 44 playing in the slot 46 formed in the guiding bracket. The upper end of the guideway is closed by a cap 48 which forms a stop for engaging the end of the gripper rod and limiting its upward movement. In this device the cutter blade 50 for severing the thread as it is gripped by the gripper fingers is formed on one of the fingers 38, instead of on the end of the 40 sleeve 40. The guideway for the sleeve 40 extends downwardly and rearwardly towards the work and is so located that the line of movement of the sleeve crosses the locking thread close to the point at which 45 the thread enters the work. The grippers and cutter are thus mounted to move bodily towards and from the upper surface of the work and when in retracted position do not interfere with the manipulation of work by the operator or obstruct his view.

During the sewing the thread gripper bars and the sleeves surrounding them are in retracted position, and the gripper fingers are open, as indicated in Figs. 3 and 8 to 12.

55 When the threads are to be severed and held at the end of the sewing the sleeves are advanced, and by their frictional engagement with the gripper rods carry the gripper fingers forward so that they pass on opposite sides and embrace the needle and locking threads, as indicated in Figs. 13 to 16. When the gripper fingers reach this position the advance movement of the gripper rods is arrested by the engagement of 60 their radial projections with the ends of

the slots in which they play, and the continued forward movement of the sleeves closes the grippers and severs the threads close to the work, as indicated in Figs. 18 to 20. The sleeves are then partially retracted, carrying the gripper rods with them into the position indicated in Figs. 21 and 22, or into the position indicated in Figs. 23 and 24. The parts remain in position until the beginning of the sewing, when they are moved into the position indicated in Figs. 23 and 24, if they were not moved into this position at the end of the preceding seam. In this position the gripper rods are retracted, and the gripper fingers are still closed by the sleeves. The parts remain in this position until the end of the first stitch forming cycle, holding the ends of the threads until the takeup has completed or nearly completed the setting of the stitch. 75 The rearward movement of the sleeves is then completed, during which movement they slide along the gripper rods and release the gripper fingers, so that the fingers return to normal open position and release the 80 threads.

The means for advancing and retracting the sleeve 26 comprises a gear 52 engaging rack teeth formed on the sleeve and engaged by a gear segment 54 which is secured to the lower end of a rock shaft 56. An arm 58 is secured to the upper end of the rock shaft, and is provided at its outer end with a slot 60 engaged by a pin 62 projecting from the lower end of an arm 64 which is secured to a rock shaft 66. The slot 60 is so arranged that oscillation of the rock shaft 66 and arm 64 rocks the shaft 56 to advance and retract the sleeve 26. The parts are held in normal position by the spring 68 connected with the arm 64 (Fig. 8). The sleeve 40 is advanced and retracted by a lever 70 secured to the rock shaft 66 and provided at its outer end with a slot engaging a roll 72 which is mounted on a pin 74 projecting from the sleeve through a slot in its guiding bracket 42.

The mechanism for rocking the shaft 66 to actuate the thread cutters and holders comprises a cam lever 76 mounted to turn freely on the shaft 66 and provided at its inner end with a roll engaging a cam groove 78 formed in a disc secured to the cam shaft of the machine. The means for connecting the cam lever to the shaft 66 comprises a coupling bolt 80 mounted in the short arm of the lever, and arranged to engage a hole 82 formed in one arm of the lever 70 which is secured to the shaft. The coupling pin is normally held out of engagement with the hole 82 by a spring 84, as indicated in Fig. 6. When the thread cutters and holders are to be actuated, the coupling pin is forced forward and engages the hole 82, as indicated in Fig. 5. The pin is retained in this position 130

tion by a locking bolt 86 which passes through a slot in the pin, and is provided with a head adapted to engage a recess 88 in the side of the pin. The bolt is pressed forward by a flat spring 90. The bolt is disengaged from the pin by the engagement of its inner end with the cam disc when the end of the cam lever engages the lowest part of the cam groove 78, as indicated in Figs. 4 and 8. When the thread cutters and holders are to be actuated, the coupling pin is pressed inward against the tension of the spring 84, and in the construction shown the means for thus moving the pin comprises a spring plate 92 arranged to engage the inclined end of the pin and carried on the lever 94, which is automatically actuated upon stopping the machine to unlock and lift the presser foot, preparatory to removal of the work. The means for actuating this lever is controlled from the stop mechanism of the machine, and since the actuating mechanism for the thread cutters and holders is rendered active by the movement of this lever, the proper timing of these devices so that their action cannot precede the substantial completion of the last stitch forming cycle is ensured. When the lever 94 is swung backward, just prior to the final stopping of the machine, the spring plate 92 presses against the end of the coupling pin 80 and presses it inward against the tension of the spring 84. When the end of the lever enters the low part of the cam groove 78 the pin registers with the hole 82 in the lever 70 and enters the hole, thus connecting the cam lever with the rock shaft 66 so that the shaft is rocked as the end of the cam lever rides up the high part of the cam 78 to actuate the thread holders and cutters to grip and cut the threads as above described. As the cam shaft comes to stopping position the end of the cam lever rides part way down the high part of the cam, or into the position indicated at 96 in Fig. 8, thus retracting the thread cutters and holders to the position indicated in Figs. 21 and 22. When the end of the cam lever moves out of the low part of the cam groove the locking pin 86 moves forward into locking position, as indicated in Fig. 5. When the machine is started the end of the lever rides into the concentric part of the cam groove, retracting the cutters and holders to the position indicated in Figs. 23 and 24, the locking bolt 86 retaining the coupling pin in engagement with the hole 82 after the lever 94 has moved forward into the position which it occupies during the sewing. As the cam shaft completes its first revolution at the beginning of the sewing, the end of the cam lever 76 enters the low part of the cam groove, thus fully retracting the sleeves of the thread cutters and holders, and also bringing the end of the locking bolt 86 against the periphery of the cam disc, so that the bolt is disengaged from the coupling pin. The pin is immediately withdrawn from the hole 82 in the lever 70, thus disconnecting the cam lever from the rock shaft 66, so that during the continuation of the sewing the cam lever oscillates idly and the thread cutters and holders remain in their retracted positions.

The mechanism for automatically operating the lever 94 upon the stopping of the machine is illustrated in Fig. 27, and is fully shown and described in Patent No. 1,233,539 above referred to. This mechanism comprises a lever 98 which is pivoted upon the hub of a lever 100, so that it may swing laterally into and out of the path of a cam 102 on the driving shaft of the machine. The lever 100 is connected by a link 104 with the upper end of a lever 106. The pivot pin which connects the end of the link with the lever 106 projects laterally into position to engage a screw 108 carried by an arm 110 which is secured to one end of a rock shaft 112. An arm 114 secured to the other end of the rock shaft has its upper end connected by a link 116 with the lever 94. During the sewing the lever 98 is held out of the path of the cam 102 by one arm of a 3-arm lever 118 which engages a screw carried in one arm of the lever 98. Another arm of the lever 118 is connected by a link 120 with a locking bolt 122 which is mounted in the spring pressed carrier slide 124 and is arranged to engage a socket in the end of the cam lever 126 which controls the throwing in and out of the low speed clutch which forms a part of the stopping mechanism. The other arm of the 3-arm lever carries a roll 128 arranged to be engaged by the end of a cam lever 130 which is connected to the upper end of the treadle rod 132 through which the main driving clutch lever 134 is operated to engage and disengage the driving clutch 136. During the sewing the treadle is depressed and the cam lever 130 acts through the 3-arm lever to hold the locking bolt out of engagement with the cam lever 126 to hold the lever 98 out of the path of the cam 102. When the treadle is released at the completion of the sewing, the cam lever 130 is raised, and the 3-arm lever is released so that the locking bolt is free to enter the socket in the cam lever 126 when this lever is swung into such position that the socket registers with the pin. When the pin snaps into the socket in the lever, the cam groove which engages the other end of the lever acts to engage the low speed braking and driving clutch at a predetermined point in the rotation of the driving shaft, and then to disengage the clutch at a predetermined point. The upward movement of the bolt is thus rendering the stopping mechanism active also rocks the 3-arm lever 118 so that the

lever 98 is swung into the path of the cam 102. As the cam shaft completes its final revolution the cam 102 acts through the lever and connections described to rock the lever 94 and render the thread cutting and holding devices active. When the treadle is depressed to start the machine, the lever 98 is swung laterally out of the path of the cam 102, and the lever 94 is moved forward 10 to normal running position by the spring 138.

While it is preferred to employ the specific construction and arrangement of parts shown and described in embodying the invention in the machine illustrated, it will be understood that this construction and arrangement is not essential to the broader features of the invention, but may be varied or modified as found desirable or best suited 20 to the construction and mode of operation of the machine in which it is to be embodied. It will also be understood that the invention is not confined in its application to a machine, in which the shoe is presented and the 25 machine controlled by the operator, but may also be embodied with advantage in automatic machines.

Having explained the nature and object of the invention, and specifically described one 30 form of mechanism in which it may be embodied, what is claimed is:—

1. A sewing machine having, in combination, stitch forming and work feeding devices including a hook needle, a looper for laying a thread in the hook of the needle and locking thread mechanism, mechanism for actuating the same to sew a continuous seam, and means for severing and holding the needle and locking threads at the completion of the seam.

2. A sewing machine having, in combination, stitch forming and work feeding devices including a hook needle, a looper for laying a thread in the hook of the needle and locking thread mechanism, mechanism for actuating the same to sew a continuous seam, and thread severing and holding means arranged to sever the needle thread and to hold it between the looper and the work and to sever the locking thread and to hold it on the opposite side of the work.

3. A sewing machine having, in combination, stitch forming and work feeding devices including a hook needle, a looper for laying a thread in the hook of the needle and locking thread mechanism, mechanism for actuating the same to sew a continuous seam, and thread severing and holding means arranged to sever the needle thread between the looper and the work and to sever the locking thread and to hold it on the opposite side of the work.

4. A sewing machine having, in combination, stitch forming and work feeding devices including a hook needle, a looper for

laying a thread in the hook of the needle and locking thread mechanism, mechanism for actuating the same to sew a continuous seam, and means for severing the needle and locking threads at the completion of the 70 seam.

5. A sewing machine having, in combination, stitch forming and work feeding devices including a hook needle, a looper for laying a thread in the hook of the needle and locking thread mechanism, mechanism for actuating the same to sew a continuous seam, and mechanism acting automatically upon stopping the machine to engage and hold the locking thread between the locking 75 80 thread mechanism and the work.

6. A sewing machine having, in combination, stitch forming and work feeding devices including a hook needle, a looper for laying a thread in the hook of the needle and locking thread mechanism, mechanism for actuating the same to sew a continuous seam, and mechanism acting automatically upon stopping the machine to engage and hold the needle and locking threads.

7. A sewing machine having, in combination, stitch forming and work feeding devices including a hook needle, a looper for laying a thread in the hook of the needle and locking thread mechanism, thread cutters and holders for the needle and locking threads, normally inactive actuating means therefor, and means for rendering the actuating means active upon stopping the machine.

8. A sewing machine having, in combination, stitch forming and work feeding devices including a hook needle, a looper for laying a thread in the hook of the needle and locking thread mechanism, stop mechanism therefor, devices for cutting and holding the needle and locking threads, and actuating mechanism for said devices rendered active upon throwing in of the stop mechanism.

9. A sewing machine having, in combination, stitch forming and work feeding devices including a hook needle, a looper for laying a thread in the hook of the needle and locking thread mechanism, stop mechanism therefor, devices for cutting and holding the needle and locking threads, and actuating mechanism therefor controlled from the stop mechanism.

10. A sewing machine, having, in combination, stitch forming mechanism including a hook needle and looper, a thread cutter and holder, actuating means therefor including an idly oscillating lever and a coupling pin for rendering the lever active to actuate the thread cutter and holder, and means for operating the coupling upon stopping the machine.

11. A sewing machine, having, in combination, stitch forming mechanism including

a hook needle and looper, stop mechanism therefor including a locking bolt for rendering the stop mechanism active, a thread cutter and holder, and actuating mechanism therefor controlled by the locking bolt.

12. A sewing machine, having, in combination, stitch forming mechanism and thread cutting and holding mechanism comprising a gripper rod provided with thread gripping fingers, a sleeve surrounding and frictionally engaging the rod, and means for reciprocating the sleeve and for limiting the movement of the rod with the sleeve.

13. A sewing machine, having, in combination, stitch forming mechanism and thread cutting and holding mechanism comprising a rod provided with spring gripper fingers, a sleeve surrounding the rod, and means for advancing and retracting the sleeve and rod together and independently.

14. A sewing machine, having, in combination, stitch forming mechanism and thread holding mechanism comprising a rod having spring gripper fingers, a sleeve surrounding the rod, means for relatively reciprocating the sleeve and rod to close and open the gripper fingers, and means for severing the thread.

15. A sewing machine, having, in combination, stitch forming mechanism and thread cutting and holding mechanism comprising a rod having spring gripper fingers, a sleeve surrounding the rod, means for relatively reciprocating the sleeve and rod to close and open the gripper fingers, and a cutter blade on the sleeve for severing the thread.

16. A lock stitch sewing machine, having, in combination, stitch forming mechanism comprising a curved hook needle, a looper and a loop taker, a work support, a thread cutter and holder arranged to cut and hold the thread passing from the looper through the needle opening in the work support, and a thread cutter and holder arranged to cut the locking thread.

17. A lock stitch sewing machine having, in combination, stitch forming and work feeding devices including a curved hook needle, a looper for laying a thread in the hook of the needle and a loop taker, mechanism for actuating the same to sew a continuous seam, a thread holder and cutter arranged to cut and hold the thread passing from the looper to the final stitch of the seam, and a thread cutter and holder arranged to cut the thread leading from the loop-taker to the final stitch of the seam.

18. A lock stitch sewing machine having, in combination, stitch forming mechanism including a curved hook needle, a looper for laying a thread in the hook of the needle, and a loop-taker, shoe supporting and guiding devices for presenting the outsole of a shoe to the stitch forming mechanism, and

means for severing the threads at the completion of the outseam and for holding the ends of the threads in proper relation to the stitch forming mechanism for the starting of the succeeding seam.

19. An outsole shoe sewing machine having, in combination, shoe supporting and guiding devices comprising a work support and a presser foot arranged to receive between them the projecting edge of the sole of a lasted shoe, lock stitch sewing mechanism constructed and arranged to sew the outseam of the shoe, and means acting automatically to sever both threads at the completion of the sewing.

20. An outsole shoe sewing machine having, in combination, shoe supporting and guiding devices comprising a work support and a presser foot arranged to receive between them the projecting edge of the sole of a lasted shoe, lock stitch sewing mechanism constructed and arranged to sew the outseam of the shoe, and means for severing both threads and for holding the severed ends on opposite sides of the work at the completion of the outseam.

21. An outsole shoe sewing machine having, in combination, shoe supporting and guiding devices comprising a work support and a presser foot arranged to receive between them the projecting edge of the sole of a lasted shoe, lock stitch sewing mechanism constructed and arranged to sew the outseam of the shoe, and mechanism acting automatically upon stopping the machine to sever both threads.

22. An outsole shoe sewing machine having, in combination, shoe supporting and guiding devices comprising a work support and a presser foot arranged to receive between them the projecting edge of the sole of a lasted shoe, lock stitch sewing mechanism constructed and arranged to sew the outseam of the shoe, and mechanism acting automatically upon stopping the machine to engage and hold the threads between the work and the stitching mechanism.

23. An outsole shoe sewing machine having, in combination, shoe supporting and guiding devices comprising a work support and a presser foot arranged to receive between them the projecting edge of the sole of a lasted shoe, lock stitch sewing mechanism constructed and arranged to sew the outseam of the shoe, thread cutters and holders for the threads, normally inactive actuating means therefor, and means for rendering the actuating means active upon stopping the machine.

24. An outsole shoe sewing machine, having, in combination shoe supporting and guiding devices comprising a work support arranged to enter the crease between the sole and upper and engage one surface of the projecting edge of the sole of a lasted shoe

and a presser foot arranged to engage the opposite surface of the projecting edge of the sole, sewing mechanism constructed and arranged to sew the outseam of the 5 shoe, a thread severing device mounted in the work support, and means for actuating said device to sever the thread at the completion of the sewing while the shoe is in position between the work support and 10 presser foot.

25. An outsole shoe sewing machine having, in combination, shoe supporting and guiding devices comprising a work support and a presser foot arranged to receive between them the projecting edge of the sole 15 of a lasted shoe, sewing mechanism constructed and arranged to sew the outseam of the shoe, a thread severing device mounted in the work support and arranged to sever the 20 thread close to the work substantially in the plane of the work engaging surface of the work support, and means for actuating said device to sever the thread at the completion of the sewing while the shoe is in position 25 between the work support and presser foot.

26. An outsole shoe sewing machine having, in combination, shoe supporting and guiding devices comprising a work support

and a presser foot arranged to receive between them the projecting edge of the sole 30 of a lasted shoe, sewing mechanism constructed and arranged to sew the outseam of the shoe and a thread severing device mounted in the work support to move towards and from the work in a path inclined 35 to the work engaging surface of the support and sever the thread substantially in the plane of the work engaging surface of the work support while the shoe is in position between the work support and presser foot. 40

27. An outsole shoe sewing machine having, in combination, shoe supporting and guiding devices comprising a work support and a presser foot arranged to receive between them the projecting edge of the sole 45 of a lasted shoe, lockstitch sewing mechanism constructed and arranged to sew the outseam of the shoe, and a thread severing device mounted to move bodily towards and from the surface of the work engaged by the 50 presser foot and sever the locking thread close to the point at which it enters the work while the shoe is in position between the work support and presser foot.

ALFRED R. MORRILL
